(57) **CLAIM**

The ornamental design for a light fixture, as shown and described.

DESCRIPTION

FIG. 1 is a perspective view of a light fixture in accordance with my design, illustrating adjustable positions;

FIG. 2 is a bottom elevation view of the light fixture in accordance with my design, illustrating adjustable positions;

FIG. 3 is a top elevation view of the light fixture in accordance with my design, illustrating adjustable positions;

FIG. 4 is a front plan view of the light fixture in accordance with my design, illustrating adjustable positions;

FIG. 5 is a back plan view of the light fixture in accordance with my design, illustrating adjustable positions;

FIG. 6 is a side elevation view of the light fixture in accordance with my design, illustrating adjustable positions; and,

FIG. 7 is an opposite side elevation view of the light fixture in accordance with my design, illustrating adjustable positions.

The broken lines showing environmental structure are for illustrative purposes only and form no part of the claimed design.

The light fixture of FIGS. 1 and 4-7 is shown with a portion broken away to indicate indeterminate length.
